(57) **CLAIM**

The ornamental design for a manure fork head, as shown and described.

DESCRIPTION

FIG. 1 is an elevated perspective view of a manure fork head according to the invention.

FIG. 2 is a top view of the manure fork head according to FIG. 1.

FIG. 3 is bottom view of the manure fork head according to FIG. 1.

FIG. 4 is a front view of the manure fork head according to FIG. 1.

FIG. 5 is a rear view of the manure fork head according to FIG. 1; and,

FIG. 6 is a side view of the manure fork head according to FIG. 1.

The broken line showing of the handle is included for the purpose of illustrating environment and forms no part of the claimed design.

1 Claim, 4 Drawing Sheets

FIG. 1

FIG. 3
